UNITED STATES PATENT OFFICE

111,073

DESIGN FOR A KNIFE

Howard L. Fischer, St. Paul, Minn.

Application July 6, 1938, Serial No. 78,312

Term of patent 14 years

To all whom it may concern:

Be it known that I, Howard L. Fischer, a citizen of the United States, residing at St. Paul, county of Ramsey, and State of Minnesota, have invented a new, original, and ornamental Design for Knives, of which the following is a specification, reference being had to the accompanying drawing forming part thereof:

I claim:

The ornamental design for a knife, as shown and described.

HOWARD L. FISCHER.
